CLAIM

The ornamental design for an infant bed safety sheet, as shown and described.

DESCRIPTION

FIG. 1 is a perspective view of an infant bed safety sheet showing my new design in use with a baby bed;

FIG. 2 is a perspective view of the infant bed safety sheet removed from the baby bed;

FIG. 3 is a front view thereof;

FIG. 4 is a back view thereof;

FIG. 5 is a top view thereof;

FIG. 6 is a bottom view thereof;

FIG. 7 is a right side view thereof;

FIG. 8 is a left side view thereof; and,

FIG. 9 is an exploded view thereof.

In the drawings, the broken lines showing the baby bed illustrate environment and form no part of the claimed design.
